UNITED STATES PATENT OFFICE.

THOMAS R. LOWERRE, OF NEW YORK, N. Y.

BOTTLE-CORKING MACHINE.

SPECIFICATION forming part of Letters Patent No. 297,943, dated April 29, 1884.

Application filed October 4, 1883. (No model.)

To all whom it may concern:

Be it known that I, THOMAS R. LOWERRE, a citizen of the United States, and a resident of New York, in the county and State of New York, have invented a new and useful Improvement in Bottle-Corking Machines, of which the following is a specification.

The object of my invention is to provide an improved bottle-corking machine, by which, in addition to the ordinary operation of pushing the cork into the neck of the bottle, the cork, previous to insertion, will be slit, and a short piece of cord or wire will be automatically inserted in the slit thus made and left therein for use as a means of afterward extracting the cork without the aid of a cork-screw.

The machine is especially designed for the practical application of the principle of construction described in my patent for improvement in bottle-corks, dated January 3, 1882, and numbered 251,908.

The invention will be hereinafter fully described with reference to the accompanying drawings, in which—

25 Figure 1 is a side elevation of a machine constructed according to my present invention. Fig. 2 is a rear elevation of the same, or as seen in the direction of arrow 1 in Fig. 1. Fig. 3 is a front view, showing the general 30 appearance of the machine, mounted upon a working-table, and connected to a treadle for operating it. Fig. 4 is a view explanatory of the manner in which the cork and cord are held, and the relative positions of parts when 35 the plunger has descended to the cork. Fig. 5 is a detail side view of the device in which the cork is held. Fig. 6 is a cross-section of the same, taken on the line $x-x$ of Fig. 5. Figs. 7 and 8 are a side view and an end view, respectively, of the cork-slitting knife.

A is the frame of the machine, and may be made of wood and strengthened by braces, as in Figs. 1 and 2; or it may be cast or otherwise formed in one piece, as shown in Fig. 3, the latter construction being the one which I prefer. The frame A is provided with an upper and a lower head, or horizontal projections a and a' , to which are fastened, at opposite sides, vertical guide-bars a' , between which 45 is fitted to slide the block B, to which the plunger b is attached. The lower end of the

plunger is detachable, having for this purpose a shank entering a socket and held by a set-screw, b' , so that it may be removed and replaced with one of different size, according to 55 the size of the cork and hole in the bottle.

To the block B, directly between the guides a' , is secured a downward-projecting rod, b'' , whose lower end is so connected with a treadle that, by depressing the latter, the plunger b 60 will descend, for the purpose of pushing the cork into the bottle-neck. When the pressure is removed from the treadle, the block and plunger are caused to rise by the pressure of a spiral spring, b'' , surrounding the bar b' , and 65 interposed between a stationary portion of the frame A and the block B.

C is a lever or bar which carries the knife and cord-spool. The lever C is pivoted to the head A, directly above, and in the center line 7c with the plunger, and has a short arm, c , by which, and a connecting-rod c' , it is connected to the block B. Oppositely to the arm c the lever C is bent downward, and has at its lower end an arm, c'' , projecting in the same direction, and about parallel with the arm c . The knife D is adjustably attached, by means of slots d and screws d' , to the end of the bar c'' , and is so located, as seen in the drawings, that when the plunger descends, and by the downward pull on the rod c' and arm c , caused thereby, the lever C is oscillated upon its fulcrum c' , the inclined and sharp edge of the knife will pass through and across, and thus slit the lower end of the cork. 85

E is a spool upon which the cord or wire is wound. The spool E is pivoted between brackets e , secured to the bar C. The cord e' passes from the spool E, underneath the arm c'' , and through the hole d'' , in the end of the said 90 arm, beneath the knife. It thence passes up through a hole, d'' , in the knife itself, the knife being curved in rear of the cutting-incline, so that the highest point d'' of the cutting-edge is at a higher elevation than the upper end of 95 the hole d'' , through which the cord passes. By this construction of the knife it is evident that in passing through the cork a clear space is cut for the cord, the slit being kept open by the knife, while the cord is simultaneously entered and the slit closes upon the cord when the knife has completely passed through. As 100

the plunger keeps descending, the lever C is swung off enough to allow the knife D to pass clearly through and beyond a pair of shears consisting of a stationary jaw, F, a movable jaw, F', pivoted at f to the stationary jaw, and an adjustable connecting-rod, f', the latter being pivoted with one end in a slot to the rear end of the jaw F' and with its other end to a bar, G, secured to the back of the sliding block B, by the downward movement of which the shears are operated. As the plunger still further descends, the cord e' is first clipped off by the said shears, and then the cork is pressed through its holder and into the neck of the bottle, leaving the ends of the cord projecting above the bottle, so that they may be tied in a knot, for convenience in afterward extracting the cork. The stationary jaw F of the shears is fastened to, or preferably formed in, one piece with and at right angles with the slotted bar G', by screws or bolts to the frame A, or to the lower end of the guides a', the bars G' and G being both slotted and fastened in a similar manner.

25 The object of slotting the bars G G' is to allow of sliding them so as to adjust the distance of the shears from the center of the plunger, and thereby the length of the piece of cord to be cut off, the opposite end of the said piece being held by the hand, as in Fig. 4. It will be noticed that by not cutting the cord until the knife D has passed a distance beyond the shears, a portion of the cord always is left projecting from the knife, as in Fig. 1, and readily accessible to be grasped by the fingers.

H is a holder, in which the corks are successively inserted to be operated upon. The holder consists simply of a plate, h, having holes h', for securing it to the machine, and a lug, h², with a hole in which the cork is inserted.

In order to prevent the lower end of the cork, which projects beyond the lug h², from being broken off or bent by the passing knife, the said lug h² is provided on the side toward which the knife passes with a forward projecting stop, h³, against which the side of the cork bears while the knife cuts, a slot, h⁴, being made through the said stop h³, so as not to impede the free movement of the knife, which, on leaving the cork, passes out through the said slot. The hole d', at the rear of the cutting-edge, may be made 55 in a separate loop or tube, or any other contrivance adapted to receive the cord, and to hold it in the proper position relative to the

knife. By the vertical slots d and the fastening device d' the knife can be raised or lowered, as the case may require, so as to cut the cork to the proper depth.

Having thus described my invention, I claim as new and desire to secure by Letters Patent—

1. In a bottle-corking machine, the combination, with the ordinary plunger b, of a knife 65 provided with a cord or wire, and arranged to slit the lower end of the cork and leave a portion of the cord therein just before the cork is driven into the bottle, substantially as and for the purpose specified. 70

2. In a bottle-corking machine, the combination, with the descending plunger b, of the knife D, having an inclined cutting-edge, and a hole, d', in rear of and a little below the highest point of the cutting-edge, said knife 75 being arranged to move transversely to the motion of the said plunger, substantially as and for the purpose set forth.

3. In a bottle-corking machine, the combination, with a descending plunger, b, and the 80 cord-carrying knife D, moving transversely to the said plunger, of the shears F F', having its movable jaw F' connected to receive its motion from the movement of the sliding block B and plunger, substantially as specified. 85

4. In a bottle-corking machine, the combination of the plunger-carrying sliding block B, the lever C, oscillated by the movement of the said block, and provided with a cord-spool, E, and having upon its lower arm, c², the cord-carrying cutting-knife D, moving by the oscillation of the lever C transversely to the plunger, substantially as and for the purpose set forth. 90

5. In combination with the plunger b and the 95 knife D, moving transversely to the plunger, the cork-holder H, provided with the perforated lug h² and slotted stop h³, substantially as and for the purpose set forth.

6. In combination with a plunger-block, B, 100 and with the cord-carrying knife D, moving transversely to the said block, the shears F F', adjustable link f', and the slotted bars G G', for adjusting the length of the cord, substantially as specified. 105

In testimony that I claim the foregoing as my invention I have signed my name, in presence of two witnesses, this 2d day of October, 1883.

THOMAS R. LOWERRE.
